(57) **CLAIM**

The ornamental design for a watch, at least substantially as shown and described.

DESCRIPTION

FIG. 1 is a perspective view of a watch showing my design; FIG. 2 is a top plan view thereof;

FIG. 3 is a bottom plan view thereof;

FIG. 4 is a side elevation view thereof;

FIG. 5 is an opposite side elevation view thereof;

FIG. 6 is a front end view thereof;

FIG. 7 is a back end view thereof; and,

FIG. 8 shows an alternative embodiment of the top plan view of my watch design, claiming the design irrespective of a particular watch face.

The broken lines shown in FIG. 8 on the casing are for illustrative purposes only and form no part of the claimed design. The broken lines merely show the environment in which claimed design may be used.
